UNITED STATES PATENT OFFICE.

ALOIS RIEDLER, OF BERLIN, GERMANY.

PISTON FOR INTERNAL-COMBUSTION ENGINES.

1,270,663.

Specification of Letters Patent. Patented June 25, 1918.

Application filed October 12, 1917. Serial No. 196,277.

To all whom it may concern:
Be it known that I, ALOIS RIEDLER, a subject of the Emperor of Germany, residing at No. 7 Rauchstrasse, Berlin, Germany, have invented certain new and useful Improvements in Pistons for Internal-Combustion Engines; and I do hereby declare the following to be a clear, full, and exact description of the invention, such as will enable others skilled in the art to which it appertains to make and use the same, reference being had to the accompanying drawing, and to letters or figures of reference marked thereon, which form a part of this specification.

In pistons of internal combustion engines having a comparatively small cylinder diameter and running at a high speed any special cooling devices for the bottom of the piston may be dispensed with. The piston bottom is consequently only cooled indirectly by the cooling water of the cylinder. The heat flows from the bottom of the piston through the material to the wall of the cylinder and passes then from the latter into the cooling water.

The central portion of the piston bottom lying farthest away from the cooled cylinder walls is not sufficiently protected from overheating as the heat taken up by this portion is accumulated in the outer zones of the piston bottom, which are also overheated.

The central portion of the hitherto known piston bottoms is thus too much overheated and tends to crack owing to the great heat stresses.

The object of this invention is to provide a special heat conductor for carrying off the heat from the piston bottom, said conductor being arranged on the underside of the piston bottom. The heat conductor has such dimensions, that a sufficiently great flowing section is provided for all parts of the piston bottom and that the heat may flow from said bottom to the wall of the cylinder along the paths of heat current assigned to it without being accumulated.

This invention will now be more particularly described with reference to the accompanying drawing, which illustrates a constructional example of the invention.

In this drawing:

Figure 1 is a vertical cross-section through a part of the cylinder of an internal com-

bustion engine, showing the piston reciprocating in it partly in front view and partly in section.

Fig. 2 is a vertical cross-section through the piston and

Fig. 3 shows a detail on an enlarged scale.

—b— denotes a cylinder cooled by the cooling medium —c—. In this cylinder —b— reciprocates the piston —a— with its shaft —f—. The piston bottom —d— limiting the combustion space has in the embodiment shown the shape of a flat plate; any other suitable form may be given, however, to this bottom. The piston shaft —f— is made preferably of a material which is a good conductor of heat, for instance cast iron, and the bottom —d— is made of the same material, or it may be made of steel in order to increase its strength. These constructions are well known in the art.

The characteristic feature of this invention is constituted by the heat conductor —e—, which is arranged in such a manner beneath the underside of the bottom —d— in the interior of the piston that the heat taken up by the bottom —d— flows into the heat conductor —e— and from this, owing to the difference in temperature, into the wall of the cylinder. The arrows shown in Fig. 1 illustrate how this flow of heat takes place. The heat is carried off from the different parts of the piston bottom in the direction of the greatest drop in temperature and flows thus mainly from the central portion of the bottom —d— into the heat conductor —e—. The shape of the heat conductor —e— influences the carrying off of the heat. With an increase of the cross-section from the central portion toward the piston shaft increases also the heat quantity carried off from the central portion of the bottom —d—. In order to obtain a good transmission or passage of heat in the contacting surfaces of the heat conductor —e— the end side and the cylindrical surface of the heat conductor may also be provided with grooves, instead of being made smooth. These grooves may be provided with play (see Fig. 3) in the direction of expansion of the parts touching each other in order to prevent heat stresses.

As a result of the provision of a special

heat conductor —e— on the underside of the piston bottom —d— the following advantages are obtained:

The bottom —d— of the piston may be 5 made of any suitable material and the thickness of this bottom may be reduced as the heat conductor acts also as a support for the bottom —d—. Any reduction of the thickness of the bottom —d— has the effect 10 to reduce the differences in temperature in the bottom —d— and the danger of a cracking of this bottom decrease in a corresponding manner. The heat conductor arranged beneath the piston and made of a material, 15 which is a good heat conductor, provides for sufficiently great cross-sections for carrying off the heat taken up by the piston bottom in the required manner, while the small thickness of the bottom, which is of advantage 20 with regard to the strength of the piston, may be retained.

The invention may be applied as well to single-acting as double-acting pistons.

What I claim now as my invention is:

1. A piston of the kind referred to, comprising a bottom part, a shaft part joining the bottom part and a heat conductor made of a good heat conducting material and arranged within the shaft part, the end wall and the peripheral surface of said heat conductor being in contact with the piston bottom and shaft respectively. 25

2. A piston of the kind referred to, comprising a bottom part, a shaft part joining the bottom part and a heat conductor made of a good heat conducting material and arranged within the shaft part, the end wall and the peripheral portion of said heat conductor being in contact with the piston bottom and shaft respectively and the contact 30 35 surfaces of the heat conductor, the piston bottom and shaft being provided with grooves.

In testimony that I claim the foregoing as my invention, I have signed my name.

ALOIS RIEDLER.
